(57) CLAIM

The ornamental design for a combined eye-wash container and removable cover, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a side elevational view of a combined eye-wash container and removable cover showing my new design, the opposite side elevational view being a mirror image thereto; FIG. 2 is a front elevational view thereof, the rear elevational view being a mirror image thereto;

FIG. 3 is a top plan view thereof; and,

FIG. 4 is a bottom plan view thereof.
